TIMING DEVICE FOR CONTROLLING TELEPHONE OR OTHER CIRCUITS

Sidney Connell, Washington, D. C., assignor of
eighty-two per cent to William H. Grund and
Edward H. Spindler, trustees

Application March 21, 1931. Serial No. 524,362

4 Claims. (Cl. 179—6.31)

My invention relates to an arrangement for controlling the time during which a telephone or other electric circuit is to be closed and in condition for use.

5 The object of the invention is to provide a device capable of use with various kinds of instruments, machines and apparatus for the purpose of permitting operation or use of the same for a predetermined period of time, after which the device automatically interrupts the circuit to such instrument or apparatus. The invention aims particularly to provide an arrangement for use at a telephone pay station and which will be actuated by the deposit of a coin to limit or control 10 the length of time during which the telephone may be used after the coin is inserted.

More specifically, my invention contemplates a device of simple construction, utilizing a solenoid or motor magnet and dash pot in combination with an operating member or lever which acts to control various electrical contacts, the operation of the motor magnet being initiated manually or by the deposit of a coin as in the case of a telephone circuit.

25 The invention is illustrated in one form in the accompanying drawings, in which:

Figure 1 is a longitudinal sectional view of parts of a construction embodying the invention;

30 Figure 2 is an end elevation of the construction shown in Figure 1;

Figure 3 is a vertical section of a slightly modified arrangement of dash pot;

Figure 4 is an enlarged detail of one of the contacts or switches employed; and

35 Figure 5 is a diagrammatic view showing the electrical circuits employed in my construction when applied to the control of a telephone circuit.

40 To illustrate the utility and operation of my invention, I have shown it applied to a telephone such, for instance, as a dial phone used in the booths or public pay stations of a telephone system and operated by depositing a coin in a typical slot machine, but it will be understood that the invention is adapted for use with various other instruments, machines and apparatus for controlling or measuring a predetermined period of time during which such instruments may be operated.

45 In the diagram of Figure 5, the main telephone lines are indicated at 1 and 2 and connected thereto is the circuit to be controlled which is indicated generally at 3 and which, with certain additional features hereinafter noted, is a well

known form of telephone circuit. This circuit includes the usual receiver 4 and transmitter 5. In addition this circuit, or branches thereof, includes the contact 6, the contact 3a and marginal relay 3b. The contact 6 controls outgoing calls from the station since, as will be clear from the drawings, when this contact is closed and the receiver 4 removed from its hook, a complete circuit will be established from one side of the main line through the transmitter and receiver and contact 6 to the other side of the line. The contact 6 is normally open but is designed to be closed for a predetermined period of time and then automatically opened, as later described. The contact 3a is closed when the armature 3d of the marginal relay 3b is attracted and this takes place when the usual alternating ringing current is sent through the line. When the contact 3a is closed by the ringing current and the receiver 4 is removed from its hook, the usual talking current from the line 1, 2 will pass through the magnet of the marginal relay 3b and energize the same to hold the armature 3d and keep the contact 3a closed as long as the receiver is off the hook. This provides for incoming calls to the station. The marginal relay is so constructed that the ordinary talking current of the line will not attract the armature 3d to close the contact 3a so this contact is normally open, but when closed by the action of the ringing current through the marginal relay, it will be held closed until the circuit is broken by placing the receiver on its hook. As noted, the contact 6 controls the outgoing calls from the station and associated with this contact is the mechanism for measuring or controlling the length of time such contact remains closed. This mechanism includes an auxiliary circuit 7 and any suitable source of current such as a battery 8 or such circuit, if desired, may be connected to the lines 1, 2. The circuit 7 contains a normally open switch 9 which is adapted to be momentarily closed by a coin in any well known manner or, in some adaptations of my invention, this switch may be manually operated. An electro-magnet 10 is also included in the auxiliary circuit 7 and when energized this magnet attracts an armature 11 which carries contacts 12 and 13. The contact 12 is in shunt with circuit 7 and when this contact is closed current continues to flow through this circuit including the magnet 10, so that contacts 12 and 13 are held closed even though the contact 9 is closed only momentarily as by the passage of a coin. The circuit 7 also includes the normally closed contact 14. The contact 13 controls a cir-

50 55 60 65 70 75 80 85 90 95 100 105 110

cuit 15 which includes a source of electrical power such as a battery 15a or, if desired, the line wires 1 and 2. The circuit 15 is the main operating circuit of the device and includes a motor magnet 5 or solenoid 16, connected to a control member 17, shown in the form of a lever, pivoted at 18 and normally held in the position illustrated by means of a spring 19. In this position the lever 17 holds the contact 6 open but when the lever is drawn 10 down this contact automatically closes. When the lever 17 approaches its lowermost position it engages and opens the contact 14. The lever 17 is drawn down when motor magnet 16 is energized and a retarding device in the form of a 15 dash pot 20 regulates the time required for the lever 17 to move down and return to its initial position. After the contact 14 is opened by the descent of the lever 17, the circuit through the magnet 10 is broken, the armature 11 is retracted, 20 opening the contacts 12 and 13, de-energizing the solenoid 16, and the spring 19 then returns the lever to its initial position.

The various parts of the device are shown as mounted on a support 30. The switch or contact 6 comprises a fixed member 6a and a resilient movable member 6b which engages the member 6a when the lever 17 moves downwardly. Normally the member 6b is held out of contact with the member 6a by the lever 17. The switch or contact 14 likewise comprises a fixed member 14a and a resilient movable member 14b which lies beneath and normally engages the member 14a but which is separated therefrom by the lever 17 when the latter moves into its lowermost position, as shown in dotted lines in Figure 1. The armature 11 is carried by a spring arm 11a which moves the armature away from the magnet 10 when the circuit thereof is broken.

The solenoid or motor magnet 16 is preferably 40 enclosed in a casing 31 which is shown as threaded into a base 32 secured to the support 30. The core of the solenoid, indicated at 33, is provided with a stem 34 pivotally connected by a pin and slot to the lever 17, the lever 17 being 45 pivoted to the support 30. The spring 19 at one end is connected to the short arm of the lever 17 and at its other end is anchored to the support 30, the tension of the spring being made variable or adjustable by means of lock nuts 35 and 36, respectively above and below the support 30. The spring 19, as before stated, is designed to 50 return the lever 17 to the position shown in Figure 1 after an operation by the lever and to retain it in such position until the next stroke or 55 operation.

The movements of the lever 17 under the action of the motor magnet 16 are controlled or measured by the retarding device 20 so that the period of time during which the switch 6 remains closed is predetermined and governed. The retarding device is in the nature of a cylinder dash pot having a head 37 secured to the support 30 and provided with a plunger or piston 38 having a stem 39 pivotally connected by pin and slot to the long end of the lever 17. As the piston 38 moves down in the cylinder, the air is more or less compressed and thus retards the action of the solenoid or motor magnet 16 and the degree of compression is controlled or regulated to govern this movement of the piston. For this purpose a port 40 is located in the wall of the cylinder near its bottom and communicates with the atmosphere, this port being controlled by a needle valve 41 adjustably mounted in a casing 42 secured to or integral with the wall of the dash pot. This

valve can be set to regulate the area of the port 40, thereby governing the resistance offered by the compressed air in the cylinder to the descent of the piston. After the piston reaches its lowermost position and starts to move upwardly 80 under action of the spring 19, as heretofore noted, such upward movement is retarded because the flow of air into the cylinder is restricted by the needle valve 41. The setting of this valve therefore measures or determines the time required for the lever 17 to make a complete downward and upward movement or the time during which the contact 6 is closed and the circuit controlled thereby is operative.

In some cases a quick downward movement of the lever 17 and a slow upward movement may be desirable. This is accomplished by the modified arrangement of Figure 3 in which a check valve 43 permits the air to readily escape when the piston moves downwardly, this valve being provided with a leak passage which permits slow ingress of air as the piston moves upwardly. By a reversal of the arrangement shown in Figure 3, i. e. by arranging the check valve to open inwardly, a slow downward movement and quick return movement of the lever 17 may be provided.

It is clear that the circuit controlled by the contact 6 may be other than a telephone circuit and that the contact 9 may be manually operated instead of automatically closed by means of a coin.

This application is a continuation in part of my pending application Serial No. 514,873, filed February 10, 1931.

Having thus described the invention, what is claimed as new and desired to be secured by Letters Patent is:

1. In combination with a telephone circuit, a contact for controlling said circuit, a member arranged to engage said contact and normally hold the same open, a motor magnet for moving said member out of engagement with said contact to permit closing of the same, a circuit for said magnet, means for opening said last mentioned circuit to de-energize said magnet and thereby permit said member to return to normal position in engagement with said contact and a spring for returning said member to normal position.

2. A construction as specified in claim 1 including a dash pot for retarding the movement of said member.

3. In combination with a telephone circuit, a contact for controlling said circuit, a lever arranged to engage said contact and normally hold the same open, a motor magnet for moving said lever out of engagement with said contact to permit closing of the same, a control circuit for said magnet, means for closing said control circuit, a normally closed contact in said control circuit, said last named contact being arranged in the path of movement of said lever and adapted to be opened thereby to de-energize said magnet, a retarding device for controlling the movement of said lever under the action of said motor magnet, and a spring for returning said lever to its normal position after said second named contact is opened.

4. In combination with the main lines of a telephone system, a station having a circuit including a receiver and transmitter and a normally open contact, a magnet adapted to be subjected to a ringing current sent over the line for closing said contact, said magnet being included in said

circuit and operating by means of the talking current to maintain said contact closed after the ringing current is discontinued, whereby incoming calls to said station may be received through 5 said circuit, a shunt circuit connected to said first named circuit, a normally open contact in said shunt circuit, said last named contact serving when closed to complete a circuit for outgoing calls from said station, a movable member ar-

ranged to normally engage said last named contact and hold it open, electrically operated means for moving said member in one direction to permit closing of said contact, means for moving said member in the other direction to bring it again into engagement with said contact and open the same, and a retarding device for retarding movement of said member. 80
